(57) **CLAIM**

The ornamental design for a food product shape, as shown and described.

DESCRIPTION

FIG. 1 is a front view of a food product shape in accordance with this invention, wherein the rear view of the food product shape is a mirror image of FIG. 1 and therefore not shown. FIG. 2 is a left end view of the food product shape of FIG. 1. FIG. 3 is a right end view of the food product shape of FIG. 1. FIG. 4 is a top view of the food product shape of FIG. 1; and, FIG. 5 is a bottom view of the food product shape of FIG. 1.
